UNITED STATES PATENT OFFICE.

CLARENCE E. HEATON, OF CHICAGO, ILLINOIS, ASSIGNEE TO WILSON BROTHERS, OF CHICAGO, ILLINOIS, A CORPORATION.

BUCKLE.

Application filed August 15, 1921. Serial No. 492,245.

To all whom it may concern:

Be it known that I, CLARENCE E. HEATON, a citizen of the United States, residing in Chicago, county of Cook, and State of Illinois, have invented certain new and useful Improvements in Buckles, of which I do declare the following to be a full, clear, and exact description, reference being had to the accompanying drawing, forming a part of 10 this specification.

The invention has relation to that class of buckles (such, for example, as are commonly used for suspenders) in which there is provided a tab-holding member to enable 15 the adjustment of the buckle to be readily effected. The object of the invention is to provide a simple, cheap and effective means for attaching a tab to the tab-holding member, and to this end the invention consists in 20 the novel construction hereinafter described, illustrated in the accompanying drawing and particularly pointed out in the claims at the end of this specification.

Figure 1 is a view in front elevation showing a portion of a suspender strap having 25 my invention applied thereto. Figure 2 is a view in side elevation. Figure 3 is a detail view of the tab-holding member. Figure 4 is a view in vertical section on the line 4—4 30 of Fig. 3.

In the drawing, my invention is illustrated as embodied in a form of buckle comprising a body portion A of ordinary construction, this body portion being shown as 35 having a depending part a with a slot therein to receive one end of a suspender strap B that is secured to the portion a, as by a line of stitches b. As shown, the body portion A is formed with outwardly turned ears 40 formed with sockets a' to receive the reduced end portions on pivots c of the tab-holding member C. In the form of the invention illustrated in the drawing, the tab-holding member C is stamped from sheet 45 metal, being made as a lever with an angular portion c² having a toothed or serrated edge to engage the suspender strap B and securely hold it against slipping when the tab-holding member is in the position shown in Figs. 50 1 and 2 of the drawings. The parts as thus far defined are of well known construction and their mode of operation will be readily understood by those familiar with this class of articles.

My improved tab-holding member C has 55 its bottom edge provided with means adapted to securely hold the tab D that is formed of flexible material and serves to enable the tab-holding member or lever to be conveniently shifted. As shown, my preferred 60 means for holding the tab comprises a loop that is formed integral with and at the bottom edge of the tab-holding member C, this loop having end portions c² connected by a bar c³. The end parts c² of the loop 65 (after the upper portion of the tab D has been passed through the loop) is pressed firmly against the tab D so as to securely clamp the tab between the bar c³ of the loop and the body of the tab-holding member C. 70 Preferably, the bar c³ is formed with teeth or points c⁴ that will embed themselves in the tab D and effectively serve to prevent its slipping from engagement with the tab-holding member. My present invention affords an extremely simple, cheap and effective means for securing the tab D to the tab-holding member. The tab D, being clamped 75 against the inner face of the member C, is held flat and in position to be readily 80 grasped.

Having thus described my invention, what I claim as new and desire to secure by Letters Patent is—

1. A device of the character described, 85 comprising the combination with the body portion, of a tab-holding member formed with a loop at its bottom edge, said loop being turned upwardly and inwardly, and a tab having its upper portion arranged 90 against the inner surface of said member and clamped between the bar of said loop and said member.

2. A device of the character described, 95 comprising the combination with the body portion, of a tab-holding member formed with a loop at its bottom edge, said loop being turned upwardly and inwardly, and a tab having its upper portion arranged 100 against the inner surface of said member and clamped between the bar of said loop and said member, the upper edge of said bar being formed with teeth to engage the tab.

CLARENCE E. HEATON.
